SAFETY RAZOR

William Harman Black, New York, N. Y.

Application March 27, 1934, Serial No. 717,657

2 Claims. (Cl. 30—12)

This invention relates to safety razors, an object of the invention being to provide a safety razor employing a square razor blade having four sharp edges, and employing means for turning the blade between the guard and clamp of the razor when the latter are separated, to present new cutting edges to be secured between the guard and clamp. This operation of turning the blade is brought about when the razor is held 10 in upright position and the blade disposed horizontally and after the clamp and the guard have been sufficiently separated to release the blade, thus permitting the blade to be turned without the necessity of touching the blade with the fingers.

A further object is to provide a safety razor of this character which may be readily assembled, easily cleaned and safely turned, and fully manipulated without the necessity of taking the 20 razor completely apart.

It is understood that I preferably employ a square blade having four sharp edges which may be sharpened from both sides, and that this blade when in operative position in the razor presents 25 two cutting edges to the guard with the other cutting edges covered, concealed, and protected between the guard and clamp.

With these and other objects in view, the invention consists in certain novel features of construction, combinations and arrangements of parts, all of which will be more fully hereinafter 30 described and pointed out in the claims.

In the accompanying drawing—

Figure 1 is a view in longitudinal section illustrating my improved razor in operative position;

Figure 2 is a view similar to Figure 1 showing the razor with the clamp slightly elevated above the guard to partially release the blade;

Figure 3 is a view in longitudinal section on 40 the line 3—3 of Figure 1;

Figure 4 is a fragmentary view similar to Figure 1, showing the parts in position to permit turning of the blade;

Figure 5 is a view in section on the line 5—5 45 of Figure 1;

Figure 6 is a view similar to Figure 5 showing the parts in different position, and

Figure 7 is a plan view of the razor blade.

My improved safety razor comprises a hollow 50 tubular handle A having integrally thereon at one end a guard B, and C represents a clamp which is adapted to clamp a blade D against the guard B. The blade D is square and has four edges 1, and is provided with four openings 2

equally spaced apart and located around a central opening 3. The blade D is provided with recesses 4 equally spaced and communicating with the central opening 3, said recesses being in line with the openings 2. The corners of the blade D are preferably cut away or recessed, as shown 60 at D', to facilitate the sharpening of the blade. The guard B and clamp C are longer than the blade so that when the blade is secured between the guard and clamp, two edges of the blade are protected, while the other two edges of the blade 65 project slightly from the side edges of the clamp over the teeth 5 of the guard in position for use.

It will be noted that both the guard and the clamp are curved transversely intermediate their edges so as to provide trough-like water passages 70 6 at opposite sides of the blade D, to permit a flushing of the razor through said passages when the razor is positioned under a faucet to thoroughly clean the razor. The clamp C is provided with a central stud 7, which is adapted to enter 75 the opening 3 in the blade and project into the hollow handle A, and is also provided with pins 8, at opposite sides of the stud 7, which are adapted to project through the openings 2 in the blade and through openings 9 in the guard to securely 80 hold the blade against turning movement in the razor. The stud 7 is appreciably longer than the pins 8 and its lower portion is tubular and internally threaded, forming a threaded socket 10 adapted to receive a threaded post 11, which constitutes a fixed or integral part of a tubular stem 12 mounted to turn in a bearing 13 in the end of the handle A. This stem 12 has an enlarged milled end 14 which normally bears against the end of the handle, and said stem being hollow 90 permits water or other fluid to flow therethrough and escape through openings 15 in the sides thereof into the handle and then flow through the handle and clean or sterilize the parts of the razor. A collar 13' is fixed on the stem above the 95 bearing 13 so as to hold the stem against longitudinal movement but permit free turning movement thereof. The post 11 is appreciably smaller in diameter than the major portion of the stem 12, so that a shoulder 16 is provided at the junction of the post and stem, and on this shoulder a collar 17 rests and is adapted to turn. The collar 17 carries a pair of fingers 18 which extend longitudinally of the handle and are adapted to engage in the recesses 4 of the blade D. A perforated cap 19 frictionally engages the post 11 and encloses a coiled spring 20 which exerts downward pressure on the collar 17 to cause said collar to frictionally engage the shoulder 16 and cause said collar to turn with the stem when per-

mitted. It will be noted particularly by reference to Figure 1 of the drawing, that when the blade is clamped in the razor, the fingers 18 are out of contact with the blade and it is only when 5 the clamp is spaced from the guard to permit the blade to assume a straight position, that the fingers operatively engage the blade, as clearly shown in Figure 2 of the drawing.

When the razor is partially open, that is to say, 10 when the clamp C is separated sufficiently from the guard B so that the side lugs are free of the guard and above it and the blade, the blade can turn between the clamp and guard, and at such time there is sufficient frictional engagement between the collar 17 and the shoulder 16, to cause 15 said collar and fingers 18 to turn when the stem is turned, and thereby cause the blade to turn a distance of ninety degrees and present other cutting edges for use.

20 To prevent the clamp from turning when the razor is partially open to allow the blade to be turned, I provide the stud 7 with keys 21 located at opposite sides thereof and movable in grooved enlargements constituting keyways 22 projecting inwardly from and integral with the walls of 25 the handle A. These enlargements 22, which constitute the keyways, not only serve as guides and holding means to prevent turning movement of the stud, but they also limit the turning 30 movement of the fingers 18, so that these fingers are permitted to turn a distance of ninety degrees only. Furthermore, it will be noted that the keys 21 and the keyways 22 are relatively short so that they are only in interengagement 35 when the clamp is moved away from the guard sufficiently to release the pins 8 from the wall of openings 9, or, in other words, when the blade D is resting on the guard and is free from interengagement with the pins 8 of the clamp. This 40 position is illustrated in Figure 4 of the drawing. When in this position the milled head 14 of the stem 12 can be turned a distance of ninety degrees, and through the medium of the engagement of the fingers 18 in the recesses 4 of the 45 blade D, will cause the blade to turn a distance of ninety degrees and present new cutting edges to the guard.

The operation is as follows: Assuming the 50 parts to be in their normal position, as shown in Figures 1 and 3 of the drawing, and it is desired to turn the four-edged blade to present other cutting edges to the guard, the operator grasps the handle A in one hand and with the other hand turns the knob 14 in a counter-clockwise direction. This turning movement causes the post 55 11 to turn in the screw socket 10 of stud 7 and unscrew from said stud, causing the clamp C to move away from the blade D and from the guard B. When the separation of the clamp is 60 sufficient to cause the pins 8 to release from the guard B and also from the blade D, and cause the pins 8 to be above the blade D, turning movement of the stem clockwise through the medium of the collar 17 and fingers 18, will cause the blade 65 D to turn a distance of ninety degrees. During the turning movement of the blade, the keys

21 are in engagement with the keyways 22 so that the clamp C is held against turning movement. By turning the stem 12 in clockwise direction, the clamp C may be further drawn down against the blade and clamp the latter against the guard, but if it is desired to entirely separate the parts of the razor, a continued turning movement of the stem in counter-clockwise direction will disconnect the stud 7 from the post 11 and the clamp and razor can be entirely separated for the purpose of removing the blade or for the purpose of inserting a new blade in position. Ordinarily, it is not necessary to entirely separate the parts for cleansing, as water flushing from the faucet can be directed not only through the trough-like channels 6 in the clamp and guard, but can be directed through the hollow stem and handle by inserting the end of the hollow stem under the stream of water. If hot water is used, it will quickly dry, and this cleansing and drying operation may be assisted by blowing through the hollow stem and handle of the razor and also blowing endwise and crosswise through the hollow troughs 6 above and below the blade.

90 While I have illustrated what I believe to be the preferred embodiment of my invention, it is to be distinctly understood that various slight changes may be made with regard to the form and arrangement of parts without departing 95 from my invention, and hence I do not limit myself to the precise details set forth, but consider myself at liberty to make such changes and alterations as fairly fall within the spirit and scope of the claims.

100 I claim:

1. A safety razor, including a guard, a hollow handle fixed to the guard, a clamp, a square blade having four edges adapted to be secured between the clamp and the guard, a rotary stem 115 in the handle, a stud on the clamp projecting into the handle and having screw-threaded engagement with the stem, a collar frictionally engaging the stem, fingers on the collar engaging the blade so that when the blade is free it can 120 be turned by turning the stem, keys on the stud, and keyways in the handle holding the clamp against turning movement when the parts are in position to turn the blade.

125 2. A safety razor, including a guard, a hollow handle fixed to the guard, a clamp, a square blade having four edges adapted to be secured between the clamp and the guard, a rotary stem in the handle, a stud on the clamp projecting into the handle and having screw-threaded engagement with the stem, a collar frictionally engaging the stem, fingers on the collar engaging the blade so that when the blade is free it can be turned by 130 turning the stem, the blade having a central opening receiving the stud, recesses in the wall of the opening receiving the fingers, short keys on the stud, and short keyways in the handle holding the clamp against turning movement when the parts are in position to turn the blade.

135 WILLIAM HARMAN BLACK.
